UNITED STATES PATENT OFFICE.

BARNET R. RAPP, OF WEST CHESTER, PENNSYLVANIA.

PRESS FOR BUTTER OR OTHER PLASTIC MATERIALS.

SPECIFICATION forming part of Letters Patent No. 392,882, dated November 13, 1889.

Application filed December 17, 1887. Serial No. 258,200. (No model.)

To all whom it may concern:

Be it known that I, BARNET R. RAPP, a citizen of the United States, and a resident of West Chester, Chester county, Pennsylvania, 5 have invented certain Improvements in Presses for Butter or other Plastic Materials, of which the following is a specification.

The object of my invention is to so construct a press for butter or other plastic material 10 that the press may be opened or closed by the movement of a single operating-lever, a further object being to provide for the close fitting of the blocks forming the lining of the press, and a still further object being to insure 15 the rigid locking of the parts of the press together during the pressing operation.

In the accompanying drawings, Figure 1 is 20 longitudinal section of my improved butter-press on the line 1 2, Fig. 2. Fig. 2 is a sec- 25 tional plan on the line 3 4, Fig. 1. Fig. 3 is a rear view of the press, looking in the direction of the arrow, Fig. 1; and Figs. 4, 5, and 6, 30 views illustrating modifications.

A is the base of the press, to a recess in 35 which is adapted a base-block, B, the latter being supported upon set-screws *a*, so that it can be readily adjusted vertically, in order to bear firmly against the lower edges of the blocks D, which line the sides and ends of the 40 mold. These blocks are carried by the opposite side plates, F, of the mold, which have projecting lugs *b* pivoted to a rod, *d*, the mold in the present instance being of rectangular form and each plate F being bent so as to form 45 two portions at right angles to each other, one portion carrying one of the side blocks of the mold and the other portion one of the end blocks of the same, the mold being divided at opposite corners, as illustrated in Fig. 2.

To provide for the adjustment of the lining-blocks of the mold and the snug fitting of the same at the corners, two of said blocks are 50 provided with screws *f*, bearing against the plates F, and are acted upon by binding-screws *g*, passing through the plates and adapted to nuts *g'*, carried by the blocks. The other two blocks are provided with similar nuts for receiving binding-screws; but instead of the 55 fixed bearing-screws *f* said blocks are pro- 60 vided with adjusting-screws *f'*, so as to regu-

late the size of the opening in which the butter or other material is to be pressed and compensate for shrinkage, thus insuring the firm bearing of the blocks against each other at the joints.

To a standard, G, at one end of the base A is 55 hung a lever, H, the long arm of which has a guide, *h*, for the stem *h'* of the plunger J of the press, said stem being connected near its upper end to an operating-lever, K, which is 60 hung by a link, *i*, to the short arm of the lever H. Hung to the lever H is a pair of arms, M, which project downward, one on each side of the joint between the opposite plates, F F, 65 of the mold, and are adapted to eyes *k* on said plates, as shown in Fig. 3, the arms being bent outward from the upper to the lower ends, so that as they are raised they have a tendency to separate the eyes *k*, and thus spread apart the plates F, the reverse operation being 70 caused on the descent of the arms.

The outer end of the long arm of the lever H is provided with a socket, H', which when the lever is depressed embraces flanges *m* on the outer meeting edges of the plates F F, as 75 shown in Fig. 2, this socket being beveled, as shown, so that as it is pressed over the flanges it will have a tendency to force the same firmly against each other, the amount of pressure being determined by the adjustment of a 80 set-screw, *n*, carried by one side of the socket. (See Fig. 2.)

When the operating-lever of the press is elevated, the plunger J strikes the under side of the long arm of the lever H and lifts the 85 same, so that the flanges at the outer meeting edges of the plates F are freed from the retaining influence of the socket H', and as the upward movement of the lever H continues the curved arms M, acting on the eyes *k* of the 90 plates F, effect the lateral separation of the latter, as shown by dotted lines in Fig. 2, so that the molded block may be readily removed from the molding-chamber of the press and a 95 fresh supply of material introduced into the same. On again depressing the operating-lever the latter acts through the medium of a spring, *p*, interposed between the same and the guide *h* on the lever H, so that the latter moves with the operating-lever. The first ef- 100

fect of this movement is the closing of the opposite sides of the press by the action of the curved arms M. As the movement continues the socket H' is brought down over the flanges 5 at the outer ends of the plates F, so as to lock the same firmly together. The plunger then enters the molding-chamber of the press and is free to be forced down into the same, so as to press the material contained therein, the 10 spring p permitting this movement of the operating-lever and plunger after the lever H has locked the parts and can have no further downward movement.

Accidental loosening of the lever H during 15 the pressing operation is effectually prevented, first, by the pressure of the spring p thereon, and, second, by reason of the lift imparted to the short arm of the lever by the operating lever K through the medium of the link i. The 20 latter construction is, however, not absolutely necessary to my invention, as the link might, if desired, be hung to a bracket on the standard G, as shown by dotted lines in Fig. 1, an arm being used in place of the lever H, as also 25 shown by dotted lines in said figure.

The arms M M are connected by a transverse bolt, t, provided with a nut, t', so that the degree of pressure exerted by said arms on the eyes k of the side plates, F, of the press 30 may be regulated in order to insure the bringing of the flanges at the outer ends of said plates closely together when the arms M are depressed.

It will be seen from the above description 35 that all the movements necessary to the opening, closing, and locking of the mold are effected by the manipulation of a single lever. Hence the press can be operated more rapidly than those in which the opening, closing, and 40 locking of the mold are effected by means independent of those employed for the pressing operation.

Although I prefer to construct the machine as shown in Figs. 1, 2, and 3, various modifications in the construction of parts of the 45 machine can be made within the scope of my invention, and in Figs. 4 and 5 some of these modifications are illustrated.

In the modified press, Fig. 4, the plunger- 50 stem k' is connected to a cross-head or handle instead of to a lever, and the lever H is replaced by a bar, H', having the socket H' and carrying the arms M, the latter being so shaped that they will fully close the mold before the 55 bar has been depressed to such an extent as to bring the socket H' over the flanges m. In this press, also, a spring, M', is shown for effecting the opening of the halves of the mold, the arms M being intended for restricting and 60 regulating the opening of the halves of the mold under the influence of the spring M' and for closing them and holding them closed. The socket H' may be dispensed with in some cases, reliance being placed upon the pressure 65 of the arms M to prevent separation of the halves of the mold. In this case the lever H

may terminate at the guide h, as shown by the dotted line in Fig. 4.

In Fig. 5 I have shown a further modification, in which the arms M, plunger J, and socket H' are hung to the lever K independently of each other. In this case the arms M should be so formed as to pass through the eyes k without imparting further pressure to the sides of the mold after the latter are closed, the socket 70 then engaging with the flanges m of the side plates, and the plunger J being finally pressed into the mold, the spring p, between the lever and socket, yielding during this latter movement; or this spring may be dispensed with 75 and the socket connected directly to the lever K, as shown in Fig. 6, if the flanges m of the mold are parallel-sided and the socket is free to slide on the same. When the lever K is raised, the cam-arms M, by their action upon 80 the eyes k, effect the separation of the halves of the mold.

For convenience, I have in the claims al- 85 luded to the parts K and H, respectively, as an operating-lever and a supplementary lever, 90 although it should be understood that these terms include bars, arms, or other equivalents of the levers, as above set forth.

I therefore claim as my invention and desire to secure by Letters Patent—

1. The combination of the separable halves 95 of the mold, the plunger, cam-arms governing the opening and closing of the halves of the mold, a socket for locking said halves of the mold, and an operating-lever acting on said plunger, cam-arms, and socket, all substan- 100 tially as specified.

2. The combination of the separable halves 105 of the mold, a plunger, an operating-lever car- 110 rying the same, a supplementary lever having cam-arms governing the opening and closing of the halves of the mold, a socket for locking said halves of the mold, and a spring inter- 115 posed between the two levers, all substantially as specified.

3. The combination of the separable halves 115 of the mold, a plunger, a supplementary lever having cam-arms governing the opening and closing of the halves of the mold, and a socket 120 for locking the halves of the mold, and an op- 125 erating-lever carrying the plunger and hung to the short arm of the supplementary lever, all substantially as specified.

4. The combination of the separable halves 120 of the mold, a plunger, cam-arms governing the opening and closing of the halves of the mold, an adjustable connection between said 125 arms, and an operating-lever acting on the arms and plunger, all substantially as specified.

5. The combination of the separable halves 125 of the mold, a plunger, cam-arms governing the opening and closing of the halves of the mold, a socket locking the halves of the mold and having an adjustable bearing-screw, and an operating-lever acting on the plunger, cam- 130 arms, and socket, all substantially as specified.

6. The combination of the side plates of the

mold and the lining-blocks therefor, with set-screws adapted to threaded openings in the side blocks and bearing at their inner ends upon the lining-blocks, and locking-screws adapted to nuts on the lining-blocks and passing freely through openings in the side plates, but having enlarged heads bearing upon said side plates, all substantially as specified.

In testimony whereof I have signed my name to this specification in the presence of two subscribing witnesses.
